UNITED STATES PATENT OFFICE.

WILLIAM W. WEEKS, OF BROOKLYN, NEW YORK, ASSIGNOR TO ELEVATOR SUPPLIES COMPANY, INC., A CORPORATION OF NEW JERSEY.

DOOR CLOSING AND CHECK MECHANISM.

Application filed April 3, 1923. Serial No. 629,552.

This invention relates to a door closer and check mechanism, and more particularly to a mechanism of this character especially adapted for use upon the doors of elevator hatchways.

One form of door-closing and check mechanism which has been heretofore used to a considerable extent comprises an oil controlled dash-pot and one or more coiled springs acting upon the dash-pot piston in a direction to produce closing movements of the door. In this form of door-closing and check mechanism it has been necessary to provide a stuffing box at the end of the dash-pot cylinder through which the piston rod passes to prevent the leakage of oil from the cylinder at this point. This stuffing box packing takes up a considerable part of the power of the door-closing spring, thereby rendering the mechanism less efficient. The springs employed in this mechanism have been coiled springs of the compression type and it has heretofore been found to be impracticable to employ a single spring inasmuch as the spring buckles under compression and is thereby thrown against the sides of the chamber in which it is enclosed, causing a great deal of friction. To avoid this difficulty in one construction heretofore produced, two springs are employed in combination with a separator interposed between the springs and mounted to slide along the piston rod, thereby complicating the construction.

The principal objects of the present invention are to improve the construction and mode of operation of door-closing and check mechanism and to produce a mechanism of this class in which the disadvantages above pointed out are wholly obviated.

With these objects in view, a feature of the invention contemplates the provision, in connection with an oil receiving chamber connected with the dash-pot cylinder, of a dash-pot cylinder having communication with the chamber so that oil on one side of the piston may flow freely from the dash-pot cylinder into the chamber during the movement of the piston in one direction in the cylinder and may thereafter flow back from the chamber into the cylinder preferably on the other side of the piston. Inasmuch as the dash-pot cylinder is thus kept filled with oil from the chamber, and the combined capacity of the dash-pot cylinder and the

chamber is greater than the quantity of oil which is used, there is no necessity to employ any packing to take up power. For the sake of convenience and compactness in the construction and arrangement of parts, the door closing spring is preferably mounted in the oil-receiving chamber.

Certain other features of the invention relate to the provision of an improved door-closing spring constructed to prevent the buckling of the spring under compression so that a single spring may be employed to produce the door-closing movement.

The invention will be clearly understood from the accompanying drawings illustrating the invention in its preferred form and the following detailed description of the construction therein shown.

In the drawings:—Fig. 1 is a view in elevation illustrating a door-closing and check mechanism embodying the present invention applied to a horizontally sliding door. Fig. 2 is a view in elevation partly in section illustrating certain parts of the mechanism shown in Fig. 1, and Fig. 3 is a detail sectional view taken substantially on the line 3—3 of Fig. 1.

As shown in the drawings of the present application, the invention is embodied in a door-closing and check mechanism applied to a horizontally sliding door. In the construction shown, the door indicated at 1 is mounted to slide horizontally upon a suitable track indicated at 2. The mechanism for opening and closing the door comprises a toggle lever consisting of two members 3 and 4 pivotally connected together at 5 of which the member 4 is pivoted at 6 to the side of the elevator hatchway and the member 3 is pivoted at 7 to the door. The toggle lever may be operated to open the door and to initiate the closing movement thereof by means of a manually operable lever 8 pivoted at 9 to the door and connected with the member 3 of the toggle lever by a link 10.

In the present embodiment of the invention, the dash-pot and door-closing spring of the door-closing and check mechanism are arranged to act upon the member 4 of the door-operating toggle lever. The dash-pot of this mechanism comprises a dash-pot cylinder 12, the lower end of which is pivoted at 14 upon a bracket 16 secured to the side of the elevator hatchway. The piston 18 of the dash-pot is mounted on the lower

2
end of a piston rod 20 which, at its upper end, is pivotally connected at 22 to a bracket 24 secured to the member 4 of the door operating toggle lever. The dash-pot cylinder is 5 filled with an oil or any other suitable liquid for controlling the movements of the piston in the cylinder. The piston 18 is arranged to fit comparatively closely in the lower part of the dash-pot cylinder and the cylinder is 10 provided with a by-pass passageway 26 through which the oil may flow in either direction during the movement of the piston in the lower part of the cylinder. The flow of the oil through this by-pass is 15 controlled by an adjustable check valve 28. The part of the dash-pot cylinder above the check valve 28 is preferably formed with a series of longitudinal grooves 30 through which the oil may flow between the piston 20 and the cylinder during the movement of the piston in this part of the cylinder.

The dash-pot piston rod 20 is acted upon by a door-closing spring 32 mounted within a chamber 34 secured to the upper end of the dash-pot cylinder. This spring at its upper end engages the end wall of the chamber 34 and at its lower end surrounds a thimble 36 secured to the dash-pot piston rod 20 and acts against a flange 38 formed on the lower part of the thimble.

In order that the oil within the dash-pot cylinder 12 may escape freely into the chamber 34 during the upward movement of the piston 18 in said cylinder, the upper end of the dash-pot cylinder is open preferably throughout substantially the entire diameter of the piston guideway in said cylinder, as shown clearly in Fig. 2. The thimble 36 engages one or more abutments 40 to limit 40 its downward movement so that there is a space between the thimble and the upper end of the dash-pot cylinder even when the thimble is in its lower limiting position, these abutments being arranged so that there 45 is ample space between the same for the flow of oil. This allows the oil to flow freely from the dash-pot cylinder between the upper end of the cylinder and the thimble into the chamber 34 at the beginning of the upward movement of the piston. In order to allow the oil discharged into the chamber 34 to flow back into the dash-pot cylinder 12 so as to keep the cylinder filled with oil at least up to the upper end of the by-pass 26, 50 the cylinder is formed with diagonal passageways 42 connecting the chamber 34 with the interior of the cylinder. These passageways are arranged so that when the piston is at the upper limit of its stroke as indicated in dotted lines in Fig. 2, their lower or discharge ends are located below the piston so that the oil from the chamber will 55 be discharged below the piston at this point in the operation of the mechanism. In the 60 use of the above mechanism sufficient oil is 65

introduced into the chamber 34 to fill the dash-pot cylinder and to partially fill said chamber.

In the operation of the mechanism described, starting with the parts in the position shown in Fig. 2 with the piston in its lower limiting position in the dash-pot cylinder which occurs when the door is closed, as the door is opened the piston moves upwardly in the dash-pot cylinder. During 70 the first part of the upward movement of the piston, a portion of the oil in the cylinder above the piston is drawn through the by-pass 26 into the central guideway in the cylinder below the piston. When the piston reaches a point in the cylinder above the upper end of the by-pass, the oil above the piston can flow freely through the grooves 30 between the piston and the walls of the cylinder, and can also flow freely into the 80 chamber 34 through the upper end of the cylinder. During the upward movement of the piston, the coiled spring 32 is of course compressed by the upward movement of the piston rod. When the door is released, the coiled spring 32 acting on the piston rod will force the rod downwardly and through its action on the levers 8 and 10 will close the door. During the first part of the downward movement of the piston in the cylinder, the oil in the cylinder will have very little retarding action on the piston as it can flow freely through the grooves 30 past the piston so that the first part of the closing movement of the door will be a relatively rapid 90 movement. When the piston however reaches the upper end of the by-pass 26, its movement will be checked by the oil below the same and will be controlled by the passage of the oil from below the piston through 100 the by-pass 26. Thus the final closing movement of the door will be a comparatively slow gradual movement.

The chamber 34 of the present construction is preferably cylindrical in cross-section 110 and is threaded into a flange 44 formed on the dash-pot cylinder. The chamber is formed at its upper end with a cap 46 threaded on the body of the chamber and provided with a plug 48 which may be removed to allow oil to be introduced into the chamber. The lower end of the dash-pot cylinder is provided with a cap 50 threaded on the body of the cylinder which may be removed when it is desired to gain access 115 readily to the interior of the cylinder.

The coiled spring 32 preferably has the construction clearly illustrated in Fig. 2. As shown in this figure, the coiled spring from a point intermediate its ends toward its upper end is formed with coils gradually diminishing in diameter and also gradually diminishing in pitch. It is found that a coiled spring of this construction will not buckle under compression. The variations 125 130

in the diameters of the coils and the changes in the pitch of the coils in the upper part of the spring are so proportioned that the spring will have substantially the same tension throughout its length.

The above door-closing and check mechanism may be employed with the dash-pot cylinder and chamber in a substantially upright position, as shown in the drawing, or 10 in an inclined position such that the oil will flow from the chamber into the dash-pot cylinder so as to maintain the cylinder filled with oil above the upper end of the by-pass. As the oil necessary to be used is much less 15 than the capacity of the spring chamber, there is no necessity for any packing to be used to take up power.

The present invention is not limited to use 20 in connection with the doors of elevator hatchways, but is capable of various other applications. It is also to be understood that the invention is not limited to the particular construction and arrangement of parts 25 of the illustrated embodiment of the invention, but that the invention may be embodied in other forms within the scope of the claims.

The plunger 18 is preferably tapered at its lower portion, as shown at 18', in which the lower surface is .015 less in diameter than 30 the upper portion. This serves to break the vacuum more quickly and has other advantages.

Having explained the nature and object 35 of the invention and having specifically described a device embodying the invention in its preferred form, what is claimed is—

1. A door closing and check mechanism having in combination a piston, a cylinder, operating connections between a door and 40 one of said parts, a chamber connected with the cylinder and communicating with the cylinder so that the controlling fluid is discharged freely from the space in the cylinder on the outer side of the piston during 45 the outward stroke of the piston and having passages discharging directly from the chamber into the space in the cylinder on the inner side of the piston when the piston is at or adjacent the position which it assumes at 50 the end of its outward stroke, said passages discharging into the space in the cylinder on the outer side of the piston except when the piston is at or adjacent the position which it occupies at the end of its outward stroke.

2. A door closing and check mechanism having in combination a piston, a cylinder having a by-pass through which the controlling fluid flows with a retarded movement 55 during the movement of the piston in the inner portion of the cylinder, a chamber connected with the cylinder and communicating with the cylinder so that the fluid on the outer side of the piston is discharged freely from the cylinder into the chamber during 60 the outward movement of the piston in the

cylinder and having passages between the outer end of the by-pass and the outer end of the cylinder through which the fluid is discharged directly from the chamber into the cylinder on the inner side of the piston 70 when the piston is at or adjacent the position which it assumes at the outward end of its stroke.

3. A door closing and check mechanism 75 having in combination a cylinder, a door closing spring within said cylinder having coils gradually diminishing in diameter from a point between the ends of the spring toward one end thereof, a by-pass in the cylinder connecting the inner end of the cylinder with another part thereof, a piston operating in the cylinder and having its inner end tapered, and connections for relatively operating the piston and cylinder from a door to carry the tapered portion of the cylinder 80 past the inner end of the by-pass during the door opening movement.

4. A door closing and check mechanism 85 having in combination a piston, a cylinder in which the piston operates having an enlarged outer portion in which the piston moves freely and a contracted inner portion in which the piston fits closely, operating connections between a door and one of said parts, a by-pass for controlling the movement 90 of fluid in the inner portion of the cylinder to control movement of the piston in this portion, a separate spring chamber of larger diameter than the cylinder mounted on the outer end of the cylinder in co-axial position 95 with relation to the cylinder, the cylinder having an opening at its outer end between the same and the chamber through which the fluid may flow freely, and a door operating a spring mounted in the spring chamber and acting on said connections to actuate the door.

5. A door closing and check mechanism 100 having in combination a piston, a cylinder in which the piston operates having a larger outer portion in which the piston moves freely, and a contracted inner portion in which the piston fits closely, operating connections between a door and one of said parts, a by-pass for controlling the movement 105 of fluid in the outer portion of the cylinder to control the movement of the piston, a separate spring chamber connected in co-axial relation with the cylinder, the cylinder having an opening at its outer end 110 through which the fluid may flow freely from the cylinder into the chamber and passages for conducting the fluid from the chamber back into the cylinder on the inner side of the piston.

6. A door closing and check mechanism 115 having in combination a piston, a cylinder in which the piston operates having a by-pass for controlling the movement of the controlling fluid to control the movement of 120

the piston in the cylinder, a spring chamber of larger diameter than the cylinder connected co-axially with the cylinder, the cylinder having an opening into the chamber of at least the full diameter of the piston, a door operating spring mounted in the chamber and acting on said connections to actuate the door, and means for discharging oil from the chamber into the cylinder on the inner side of the piston when the piston is at its outer position in the cylinder.

7. A door closing and check mechanism having in combination a piston, a cylinder having a by-pass thru which the controlling fluid has a retarded movement, the upper portion of said cylinder being provided with

a spring-containing chamber, and means for effecting communication between said spring containing chamber and the lower portion of said cylinder so that the controlling fluid flows freely from the space in the cylinder on the outer side of the piston into the lower portion of said cylinder during a portion of the outward movement of the piston, said means comprising a passage, distinct from said by-pass, thru which the fluid is discharged into the cylinder on the inner side of the piston when the piston is traversing a portion of its outward stroke.

Signed at New York, N. Y., this 2d day of April, 1923.
